[57] **CLAIM**

The ornamental design for a tumbler or similar article, substantially as shown and described.

DESCRIPTION

FIG. 1 is a side elevational view of a tumbler or similar article showing my new design, the sides not shown are similar to the side shown;

FIG. 2 is a cross sectional view thereof, taken along the lines 2—2 of FIG. 3 looking in the direction of the arrows;

FIG. 3 is a top plan view thereof;

FIG. 4 is a bottom plan view thereof; and

FIG. 5 is a cross-sectional view taken along lines 5—5 of FIG. 1 looking in the direction of the arrows.

The thickened bottom wall in FIG. 2 that would be visible through the transparent side wall in FIG. 1 has been omitted for convenience of illustration.

FIG. 1

FIG. 2

FIG. 3

FIG. 4

FIG. 5
